CAN OPENER

Josiah F. Peckham, Providence, R. I., assignor of
one-half to Hubert A. Latham, Providence, R. I.

Application June 21, 1934, Serial No. 731,681

3 Claims. (Cl. 220—49)

This invention relates to a can opener; and has for one of its objects the provision of a can opener which will be assembled with the can as a permanent part thereof.

5 Another object of the invention is the provision of a can opener which may be more easily operated than any can opener with which I am familiar.

Another object of the invention is the provision 10 of a can opener which as it operates, causes that portion of the can which covers the opening, which is to be made for access to the contents of the can, to be lifted so that it may be readily grasped by the operator of the can opener, to be 15 manipulated from an obstructing position.

Another object of the invention is the provision 20 of a can having a top wall in a generally single plane and an opening cut out of such top wall within its periphery.

25 Another object of the invention is the provision of an opening in the can, which may be of any desired shape and may be made without reference to the peripheral shape of the can in which the opening is made.

30 Another object of the invention is the use of a single thickness of stock for one of the walls of the can and the deflecting of this stock so as to provide suitable track or guide for directing a cutting member in its desired path of travel for cutting the opening and at the same time stiffen the top wall.

35 A further object of the invention is the provision of a can, which can when opened is not refillable.

40 With these and other objects in view, the invention consists of certain novel features of construction, as will be more fully described, and particularly pointed out in the appended claims.

In the accompanying drawings:

45 Fig. 1 is a perspective view of a can equipped with my opener.

Fig. 2 is a perspective view of a fragmental portion of the top of the can, showing the end of my opener as lifted and the tearing of the top 50 of the can started.

Fig. 3 is a view similar to Fig. 2 but showing the tearing operation for opening the can as almost completed.

Fig. 4 is a top plan view of the can.

55 Fig. 5 is a bottom view showing the under surface of the top wall of the can.

Fig. 6 is a sectional view illustrating the contour of the top of the can forming the guide track for the severing member.

Fig. 7 is a sectional view of a modified form of can top.

Fig. 8 is a sectional view of a different modified form of can top.

60 Fig. 9 is a top plan view of a still different modified form of can top and showing a larger can

with the opening as located eccentric to the center of the top.

Fig. 10 is a top plan view of a differently shaped can, and showing a modified arrangement of the opening device.

Fig. 11 is an elevational view of a modified form of handle for the severing member.

Some cans are provided with opening devices consisting of a key to roll up or tear a strip of the metal of the can. Such an opening device has

10 a limited application and frequently breaks or the key may become lost and in order to provide for opening the flat top of a can so that a portion of the top wall may be removed or severed to

15 such an extent that it may be bent back to expose the contents of the can in a simple and inexpensive manner without additional parts, I have provided the top wall of the can with a guide track for deflecting the stock of the can and

20 weaken a portion of the stock and then by positioning a severing member beneath this weakened top wall with its end projecting thru I may pull on this severing member to cause the same to

25 tear the weakened portion of the top wall and by arranging the guide track in a manner to deter-

mine both the size and shape of the opening I may sever the top wall in any desired shape or

size irrespective of the size or shape of the can and

without reference to its peripheral edge; and the

30 following is a more detailed description of the present embodiment of this invention illustrating the preferred means by which these advan-

35 tageous results may be accomplished.

With reference to the drawings, 15 designates

40 the bottom wall of a can with vertically rising side walls 16 which may be of any shape altho that

45 shown in Figs. 1 to 9 inclusive, illustrate a cylindrical can. Cans of this character are frequently

40 hermetically sealed and are supplied without the top wall to permit of easy filling of the can with

45 that which it is to carry, after which the top wall is placed over the open end in contact with the

50 side wall or walls 16 and then by a rolling process the edge of this top wall is sealed and firmly

55 bound to the side wall. To open a can of this character, the housewife usually inserts a pointed instrument, frequently called a can opener, and cuts the top wall at a distance spaced inwardly

50 from the peripheral edge thereof and guided by

55 this edge so that the top of the can except its

60 outer edge may be lifted or bent back to expose

At a point inwardly from the peripheral edge 18 which is rolled over the side-wall 16, the top wall is bent inwardly usually by means of a die, to provide a vertically extending track 19 presenting a guide surface 20 on the outer surface thereof which provides a guide for a flexible member 21, usually formed of a wire or any material which is sufficiently tough to tear or cut the top wall of the can adjacent the guide track. The top portion which is to be cut is shown in Fig. 6 at 22 as somewhat thinned by the pressure utilized for forcing the vertical wall 19 inwardly at its desired location and which may be further thinned by a rib on the die to indent it on the underside. A flexible member 21 lies snugly against the guiding surface 20 and against the under surface of the portion 22 of the top wall which is to be cut being positioned in the corner at the juncture of these two surfaces, as illustrated in the sectional views of Figs. 6 and 7.

One of the ends of the flexible member 21 extends thru a hole 23 in the top wall for anchoring it at this point from which it extends into engagement with the surface 20 circularly about the top 25 of the can beneath the surface 22 to a point adjacent the anchored end 23 and there passes back thru an opening 24 in the top wall of the portion 22 thereof and terminates in a loop 25 which may be formed from the wire by doubling it upon itself and fastening it by twisting as at 26, or may be formed by a separate ring 27, see Fig. 12, secured to the wire by twisting as at 28. The openings 23 and 24 may be sealed by solder, or any suitable sealing material. The loop 25 provides 30 a handle thru which a finger may be placed so that for opening the can, it is merely necessary to pull on the handle 25 which will cause the flexible member 21 to tear the thinned surface 22 at a point adjacent the wall 19, whereby the tear will 35 follow the wall 19 to form an opening of a shape and of the desired size depending upon the shape and size of the vertical wall 19 and its guide surface 20 which is pressed into the top of the can. In order that this handle portion 25 may be 40 conveniently housed in the top of the can, I have pressed into the top of the can a recess 28 at a location adjacent the opening 24 so as to receive the handle 27, see Fig. 2.

The stock inwardly from the guide or vertical 45 wall 19 may be of various configurations, I have illustrated it in Fig. 7 as raised as at 29, to be at a level substantially the same as the portion 22, altho I have indicated it in Fig. 6 as depressed thru a greater area.

In Fig. 8, instead of forming the vertical guide 50 wall 19 by forcing the guide wall or track inwardly, I have forced it up into a U-shaped formation 30 providing spaced vertical walls 31 and 32, the latter of which serves as a guide for directing the flexible member 21 in its desired course about the top of the can.

In Fig. 9, I have illustrated the top wall 33 with its portion 34 to be opened located eccentric to the center of this top wall 33 which may be conveniently used where a large container is desired to be but partially opened to permit of access thereto.

I have also illustrated in Fig. 10, a container 55 of rectangular cross section having a top wall 35 with an irregularly shaped formation generally elliptical, designated 36, which is to be opened. The guide wall designated 37, and the flexible member with its handle 38 housed in a con-

venient position for operating. This is particularly desirable where liquid is to be poured from the can as the liquid is thus better controlled in handling the same.

It will be seen that the opener which I have provided is unlimited as to the shape and size of the opening which it may cut in a surface in a single plane that is carried by the can and that it is always accessible and that the deflecting of the stock for the guide track also stiffens the 10 wall and strengthens the wall in which the guide track is thus formed.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A can top comprising a single thickness of sheet stock having a substantially annular horizontal portion, a peripheral sealing edge extending therefrom, a vertical wall extending downwardly from said horizontal portion, a web portion closing the center of the vertical wall, the entire configuration of said top being free from overhanging portions and capable of being formed between matched dies in a single pressure operation, and a flexible severing member 25 secured at the right angular juncture of said horizontal and vertical portions of said top with one end extending thru said horizontal portion and provided with a handle for engaging and pulling the same, and the other end being secured adjacent said juncture at a point spaced along said extent of the severing member from said pulling end.

2. A can top of a single piece of sheet stock comprising a substantially annular horizontal portion, a peripheral sealing edge extending therefrom, a vertical wall extending downwardly from said horizontal portion and doubled back to provide a generally U-shaped bend with the vertical portions of the formation spaced, a web portion connecting the inner edge of said U-shaped wall, the entire configuration of said top being free from overhanging portions and capable of being formed between matched dies in a single pressure operation, and a flexible severing member 40 located at the right angular juncture of said horizontal and outer vertical portions of said top with one end extending thru and fastened in said horizontal portion and the other end extending thru said horizontal portion and provided with a 45 handle to be engaged for pulling the same.

3. A can top of a single piece of sheet stock comprising a substantially annular horizontal portion, a peripheral sealing edge extending therefrom, a vertical wall extending from said portion providing a guide track, the entire configuration of said top being free from overhanging portions and capable of being formed between matched dies in a single pressure operation, a flexible severing member extending about 50 and secured adjacent said vertical wall to be guided thereby with one end extending thru the top and secured thereto and the other end extending thru said top and provided with a handle for engaging and pulling the same, and means 55 for sealing the top at the point of passing there thru of said severing member.

JOSIAH F. PECKHAM.
